UNITED STATES PATENT OFFICE

EDMUND FEY, OF SAN FRANCISCO, CALIFORNIA

SOUND RECORDING AND RECORD VENDING MACHINE

Application filed July 8, 1929. Serial No. 376,659.

This invention relates to improvements in sound recording and record dispensing machines.

An object of my invention is to provide a novel sound recording machine wherein is provided a suitable mechanism for moving a record disc into position for engagement with sound conducting and recording means.

Another object of my invention is to provide a novel sound recording machine wherein is located a mechanism for successively bringing a number of record discs into engagement with sound recording means, whereby sound records may be made thereon, and for successively dispensing the discs after the sound records have been produced thereon.

A further object of my invention is to provide a novel machine which, upon the insertion of a token therein, enables a person to record his voice on a record disc, and thereafter receive the same.

Other objects more or less apparent will present themselves or will be specifically pointed out in the description to follow.

In the accompanying drawings:

Fig. 1 is a side elevation of a sound recording and record dispensing machine constructed in accordance with my invention;

Fig. 2 is a sectional view taken on the line 2-2 of Fig. 5;

Fig. 3 is a sectional view taken on the line 3-3 of Fig. 2;

Fig. 4 is a sectional view taken on the line 4-4 of Fig. 5, showing the disc holding magazine with a number of discs therein;

Fig. 5 is a sectional view taken on the line 5-5 of Fig. 2;

Fig. 6 is a sectional view taken on the line 6-6 of Fig. 5; and

Fig. 7 is a fragmentary part of the disc positioning table showing a portion of the groove therein for controlling the movement of the sound recording means.

Referring to the drawings the numeral 1 represents a cylindrical casing having a detachable cover 2 thereon which is provided with a coin slot 3 and a sound collecting speaking tube 4. The coin slot communicates

ly inside the casing. The speaking tube communicates with sound conducting tone arm 6, which is pivotally mounted on the inside of the casing.

Suitably supported inside the casing by means of braces 7 is a stationary disc supporting member 8 which is provided centrally therein with an opening through which a vertical stationary bar 9 extends. Movable mounted on the bar 9 with its hub resting on a flanged projection 10 secured to the said bar, is a turntable 11 which is provided therein with four circular openings 12 within each of which a record disc 15 may be lodged. A cylindrical disc containing magazine 14, secured to the cover 2 with its lower edge raised slightly above the turntable 11, is normally located above one of the circular openings 12, and in a position adapted to supply record discs 15 to the said openings. The record discs 15, which are made from wax or other suitable material with suitable grooves therein for the reception of the pointed end of a stylus 16 carried by the sound conducting tone arm 6, are supported by supporting member 8 after they have become positioned inside the openings 12 in the turntable 11.

The turntable 11 is provided at points adjacent its circumferential edge and between the circular openings 12 therein, with four projections 17 which are so recessed as to receive a coin dropped through the coin chute 5. The projections 17 are also each provided at their lower edge with a slot 18 through which an upwardly extending projection 19 of a manipulating rod 20 may pass. The manipulating rod is movably mounted on the hub of turntable 11 and is adapted to move independently of the said turntable at certain times. Secured to the casing 1 at points beneath the lower end of the coin chute 5 is an arcuate shaped angle iron 21 which is adapted to support a coin dropped from the end of the said coin chute. The manipulating rod 20 extends through a horizontal slot located in the side of the casing 1, and the same may be manually moved backwardly and forwardly. When the manipulating rod 20 is positioned at one end of the

horizontal slot in the casing, a coin dropping from the end of the coin chute 5 is adapted to lodge inside the recess in one of the projections 17 of the turntable 11. The manipulating rod 20, at points adjacent where the projection 19 occurs, is provided with a vertical slot through which the coin may pass. The coin dropped from the end of the coin chute 5, into the recess of the projection 17 and the slot in the manipulating rod 20, is supported by the angle iron 21. The manipulating rod 20 upon being moved in a clockwise direction contacts with the coin supported by the angle iron 21, and presses the same against the projection 17 of the turntable 11. The coin being maintained in contact with the manipulating rod 20 and the projection 17 enables the turntable 11 to be moved in a clockwise direction with the manipulating rod 20, as long as the angle iron 21 supports the same. The openings 12 in the turntable are so positioned with reference to the ends of the angle iron 21 that a record disc 15 may be taken from the magazine 14 and carried for approximately ninety degrees before the coin supported by the angle iron drops from the end of the latter. After the coin drops from the end of the angle iron into the lower part of the casing, the manipulating rod 20 is free to move independently of the turntable. The projection 19 of the manipulating rod not being in contact with a coin, passes freely through the recesses 18 of the projections 17, thereby permitting the manipulating rod to be moved without interfering with the recording of sound waves on the record disc, as will be hereinafter described. The four openings 12 in the turntable are so positioned with reference to the projections 17, that a disc 15, upon each insertion of the coin in the coin slot 3, is permitted to be carried through an arc of approximately ninety degrees.

The tone arm 6, which is pivotally mounted on the side of the casing, is adapted to be raised and lowered to cause the pointed end of the stylus 16 to engage and disengage with the grooves of a record disc 15. The turntable is provided on its upper surface with a cam groove 22 within which a downwardly projecting pin 23 secured to the tone arm 6 is lodged. The groove 22 assumes an abrupt inward direction at points adjacent to the openings 12, as shown by the numeral 24, and at each inwardly disposed end of the abrupt part of the said groove, the latter curves outwardly as shown by the numeral 25. The inwardly disposed parts 24 of the groove are each of greater depth than the other parts of the groove, thereby providing suitable means for the lowering of the tone arm 6 when the pin 23 enters this part of said groove. The pointed end of the stylus 16 is adapted to come in contact with the grooves of a record disc 15 at points where the inwardly disposed parts 24 of the groove 22 commence. The inwardly disposed parts 24 of the groove 22 are each of sufficient length to permit the stylus 16 to travel toward the center of a record disc from the outer part thereof to the centrally disposed part where the grooves of the disc terminate. Thus when the disc 15 is rotated, the pointed end of the stylus 16 follows the record disc grooves from the outer circumferential edge of the said disc to a point adjacent its center. At the same time the stylus reaches the inwardly disposed end of the groove in the record disc 15, the pin 23 of the tone arm 6 has reached the inwardly disposed end of the part 24 of the groove 22. At this point the pin 23 is ready to enter the outwardly and upwardly disposed part 25 of the groove 22, and upon the turning of the turntable 11 by the manipulating rod 20, the said pin 23 follows the groove 22, and the tone arm 6 is so raised that the stylus 16 is disengaged from contact with the record disc 15. As the turntable 11 is turned through an arc of ninety degrees the record disc 15 which has been in engagement with the stylus 16, is brought to an opening 26 in the stationary supporting member 8, and the said disc drops into a chute 27 where it is picked up by the person operating the machine. During this procedure, the record disc located to the right of the disc which previously received the stylus 16, is carried by the turntable through an arc of ninety degrees to a point adjacent where the stylus and tone arm are positioned. The pin 23 of the tone arm 6, has during the turning of the turntable through an arc of 90 degrees, reached a point on the groove 22 where the following inwardly disposed part 24 occurs. At this point the pin 23 is again in position to drop into the part 24 of the said groove 22, and engage with the record disc 15 which has been carried to the position adjacent the tone arm.

The coin chute 5 is provided near its upper end with an insulated sleeve 28 through which a contact arm 29 movably extends. The contact arm 29 extends into the coin chute 5 and is adapted to intercept a coin and hold the same in a suspended position for a certain interval and during the time the stylus 16 is proceeding from one end of the groove in the record disc 15 to its other end. The contact arm is connected to wires 30 of a circuit leading to a source of electrical power 31 and a motor 32, one end of the circuit being connected to the coin chute 5. The motor 32 is provided with a shaft 33 which is provided with a pulley member 34 and a wheel member 35. Revolvably supported inside an opening located in the stationary supporting member 8 near the tone arm 6, by means of an upright bracket 36, is a disc supporting table 37. The table 37 is provided with a recessed hub which ro-

tatably extends into an arm of the bracket 36 and is supported by the latter. The periphery of the wheel 35 is in engagement with the periphery of the table 37, and the former 5 through the operation of the motor 32, causes the said table to rotate. Rotatably located in and supported by another arm of the bracket 36 is governor 38 which is rotatably connected through a belt 39 to the pulley 34 of the motor shaft 33. The lower end of the 10 governor is secured to a centering pin 40 which loosely projects through the hub part of the governor, the hub of the table 37 and through a central opening in a record disc 15. When the motor is rotated the balls of the governor 38 through centrifugal force move the pin 40 upwardly so the same 15 enters the central opening in the record disc 15 and centers it in a suitable position on the 20 supporting table 37 so the stylus 16 may properly follow the groove on the said disc from the beginning to the end thereof. When the motor ceases to operate the balls of the governor move toward each other and 25 permit the centering pin 40 to drop beneath the record disc 15 and the turntable 11, thereby permitting the latter to be moved through an arc of 90 degrees by the manipulating rod 20. 30 When a blank record disc 15 has been moved into position onto the supporting table 37, the tone arm 6 together with the stylus 16 are lowered by the pin 23 entering the part 24 of the groove 22. The stylus 35 thereupon engages with the groove of the record disc 15, and is in position to suitably record a person's voice spoken into the speaking tube 4. A coin dropped into the coin chute 5 contacts with the contact arm 29, 40 thereupon closing the circuit to the motor 32 which causes the said motor to operate. The wheel 35 of the motor shaft upon rotating causes the table 37 and the record disc thereon to rotate also, and the stylus 16 of the tone 45 arm 6 travels through the record groove of the disc toward the center of the latter. The pin 23 of the tone arm proceeds inwardly in the part 24 of the groove 22, and after the stylus has reached the inner terminal of the 50 record groove, the said pin has reached the point in the groove 22 where the upwardly raised part 25 commences. The record disc 15 at this time has received the records, through the vibration of the stylus in the 55 grooves thereof, of the person's voice, and the said disc is now ready to be dispensed through the chute 27.

The tone arm 6 and the contact arm 29 are connected together through a series of pivoted levers 41 which are supported on the casing 1 by an insulated bracket 41'. The levers 41 are so actuated by the pivoted movement of the tone arm 6 as the stylus 16 proceeds toward the center of the record disc 15, 60 that the contact arm 29 is sufficiently with- drawn from the coin chute 5 to allow the coin to drop downwardly and open the circuit to the motor, thereby discontinuing the rotation of the record disc 15. The coin upon dropping onto the angle iron 21 becomes positioned in contact with the manipulating rod 20 and a projection 17 of the turn table 11, thereby enabling the said manipulating rod to be moved so as to turn the turntable 70 through an arc of 90 degrees and discharge 75 the completed record disc 15 through the chute 27 and at the same time deposit another record disc on the supporting table 37, preparatory to the next operation of the machine. The pin 23 of the tone arm, upon entering the outwardly disposed part 25 of the groove 22 turns the said tone arm sufficiently to cause the levers 41 to move the contact arm 29 into the coin chute 5, where it may again intercept a coin to close the 80 circuit to the motor 32.

In order to provide means for preventing a coin from passing through the coin chute 5 while the person operating the machine is having his voice recorded on the record disc, 85 and also to prevent the manipulating rod from being moved to interfere with this procedure, a balanced bar 42 with projecting parts 43, 44 and 45 is pivotally attached to the coin chute. The projecting part 45 of the bar 42 is normally at rest against the manipulating rod 20, and when the latter is moved to the left inside the slot of the casing through which it projects, the said rod 42 because of its balanced end, moves in such 90 a manner as to cause projections 43 and 44 to enter holes in the coin chute and prevent either a coin from entering the part of the coin chute above the contact arm 29 or allowing 95 a coin dropped from the said contact arm 100 to pass all the way down through the said chute. When the manipulating rod 20 is positioned at the right hand end of the slot in the casing through which it projects and beneath the end of the coin chute, the projection 45 of the bar 42 is held by the said manipulating rod so the projections 43 and 44 are withdrawn from the coin chute, as 105 shown in Fig. 3, thereby permitting a coin to pass through the said coin chute or allow 110 another coin to proceed through the upper part of the said chute to engage with the contact arm 29. Thus while a coin is contacting with the contact arm 29 and the motor is operating, the manipulating rod 20 115 may be moved without interfering with the recording of sound vibrations on the record disc 15.

It is apparent to those skilled in the art that my improved coin controlled recording 120 machine may be constructed to assume other forms than the one shown and described, so for this and other apparent reasons I desire my invention included broadly within the 125 spirit of the appended claims.

Having described my invention, what I claim is:

1. In a sound recording machine comprising a rotatable record support, means for rotating the support, a turntable adapted to carry a plurality of records, means for actuating the turntable whereby a plurality of records may be successively delivered to and from the record support, vibration transferring ring apparatus pivotally mounted to engage with and disengage from a record on the support, and means for lowering and raising the vibration transferring apparatus, which said means comprises a projection on the said apparatus riding in a groove in the turntable.

2. In a sound recording machine comprising an enclosing casing a rotatable record support mounted in the casing, means for rotating the support, rotatable means for delivering a record to the support, a manipulator extending through the casing for operating the rotatable means, means for maintaining the record in a definite position on the support, a sound carrier pivotally mounted inside the casing adjacent the record support having vibration transferring means thereon, and means for moving the carrier whereby the vibration transferring means may be brought into engagement with a record on the record support.

3. In a sound recording machine comprising a rotatable record support, a rotatable turntable for delivering records to the record support, a motor connected to the support, an electrical circuit connected to the motor, a contact arm connected to the circuit for opening and closing the circuit to the motor, a sound carrier having vibration transferring means thereon, and means connecting the contact arm and the sound carrier, whereby upon the movement of the sound carrier the contact arm may be moved to open the circuit.

4. In a sound recording machine comprising a pivoted sound carrier having vibration transferring means thereon, a rotatable record support, a rotatable turntable for delivering records to and from the record support, means for moving the sound carrier toward the record support, electrically operated means for rotating the support, a contact arm connected to the electrically operated means, and means connecting the sound carrier and the contact arm, whereby upon the movement of the sound carrier the contact arm may be actuated.

5. In a sound recording machine comprising a pivoted sound carrier having sound transferring means thereon, a rotatable record support, a rotatable turntable for delivering records to and from the record support, means for moving the sound carrier toward the record support, electrically operated means for rotating the record

support, an electrical circuit connected to the electrically operated means, a contact arm connected to the circuit having means associated therewith for closing the circuit, and means connecting the contact arm and the sound carrier whereby upon the movement of the carrier the contact arm may be actuated to open the circuit.

In testimony whereof I have affixed my signature.

EDMUND FEY.
